UNITED STATES PATENT OFFICE

2,583,319

GRINDER ROTOR

Edgar R. Brake, Columbus, Ohio, assignor to The Jeffrey Manufacturing Company, a corporation of Ohio

Application May 6, 1950, Serial No. 160,565

1 Claim. (Cl. 241—191)

1
This invention relates to grinders and more particularly to the rotors that are employed in grinders.

An object of the invention is to provide an improved grinder rotor including cooperating expandable body and hub members or parts having cam means so constructed that when they are clamped together upon a rotor shaft the rotor becomes locked to the shaft upon which it is mounted and to each other and to removable, renewable members that carry material reducing elements.

Other objects of the invention will appear hereinafter, the novel features and combinations being set forth in the appended claim.

In the accompanying drawings:

Fig. 1 is a side view in elevation of a garbage grinder including the invention, with parts broken away and parts in section;

Fig. 2 is an end view in elevation of the grinder seen in Fig. 1, with parts broken away; and

Fig. 3 is a view in section through the rotor of the grinder, the section being taken on the line 3—3 of Fig. 1.

The garbage grinder 10 shown in the drawings includes an electric motor 11, the housing of which includes a base 12 adapted to be mounted upon any suitable support. To one side of the motor housing there is secured the body casting 13 of the garbage grinder. Body casting 13 includes a flanged side member 14 that is secured directly to the motor housing by a plurality of cap screws 15. Side member 14 of the body casting 13 includes an opening 16 through which the shaft 17 of the motor extends into body casting 13. The side member or wall 18 of body casting 13 opposite side member 14 includes a circular opening closed by a disc-like plate 19 secured to the body casting 13 by a plurality of cap screws 20. The diameter of the opening closed by plate 19 is such that a rotor assembly 21 may be inserted through it and onto the motor shaft 17.

Body casting 13 includes a feed opening 22 at its top through which garbage is fed into a grinder housing 23 formed in part by the body casting 13 and plate 19. Body casting 13 at its lower end forms an outlet opening 24 that is threaded and is received by a T 25 attached to a pipe 26 that leads to a sewer, not shown.

Body casting 13 carries two replaceable liner or wear plates 27 and 28 each secured to an inside wall thereof by bolts 29. Between the lower ends of liner plates 27 and 28 there is an arcuate perforated grid plate 30 that cooperates

2
with the rotor assembly 21 in grinding garbage. The ground garbage which passes through the perforations 31 in grid plate 30 passes downwardly through outlet opening 24 and is conveyed to the sewer through the T 25 and pipe 26.

Rotor assembly 21 includes a tapered or frusto-conical hub 33 that is split radially and axially at 34 to make it compressible. Hub 33 includes a shouldered bore 35 which opposite the split 34 provides a keyway 36. Hub 33 is carried by the shaft 17 of motor 11 with the keyway 36 being received by a key 37 in shaft 17.

Hub 33 carries a cylindrical rotor body member 38 that includes a tapered or frusto-conical bore 39 adapted to be received by the outer tapered surface of hub 33. The cylindrical rotor member 38 is split radially and axially at 39 to make it expandable. Split 39, as seen in Fig. 3, is opposite the split 34 in hub 33 when the rotor is assembled. The cylindrical member 38 fits over hub 33, and the frusto-conical surfaces of hub 33 and cylindrical member 38 cooperate to form cam surfaces which when the cylindrical member 38 is clamped upon the hub 33 cause the hub 33 to be compressed upon the motor shaft 17 and the cylindrical member 38 to be expanded. Cylindrical member 38 is clamped upon hub 33 by two cap screws 40, the heads of which seat in recesses in one side of member 38 and extend through a web thereof into hub 33. It will be seen that when cap screws 40 are tightened they will draw or clamp the member 38 over hub 33.

The cylindrical rotor member 38 is slotted to carry a key 41 and upon its outer surface it carries a plurality of relatively thin ring members 42. Each ring member 42 includes three teeth or material reducing members 43 that are equally radially spaced thereon. Each of the ring members is slotted at 44 and 45 so that the rings may be placed upon member 38, successively, rotated 180° with respect to each other. This arrangement of the rings 42 and key slots 44 and 45 permits rings 42 to be identical in construction and to be placed upon member 38 so that the teeth 43 of the alternate rings are staggered radially with respect to each other, with the key 41 positively locking the rings 42 against rotary movement upon the member 38. The ring members 42 and key 41 are retained against axial movement with respect to the cylindrical rotor member 38 by a snap ring 46 and a shoulder 47.

It will be seen that the rotor assembly 21 may be placed upon the end of motor shaft 17 by inserting it through the circular opening in side wall 18 of casting 13 and onto the end of motor

shaft 17. Proper positioning of the rotor assembly 21 upon the shaft 17 is assured because the end of the shaft engages the abutment 48 formed by the stepped bore 35 of hub 33. Upon tightening the clamp screws, the cylindrical rotor member 38 is clamped through the cooperation of the cam surfaces provided by the tapered bore of cylindrical rotor member 38 and the tapered outer surface of hub 33 to compress the latter upon motor shaft 17 and to expand the cylindrical rotor member 38 within the ring members 42. When the clamp screws 40 are loosened the rotor assembly 21 may be withdrawn from the end of the motor shaft 17 through the circular opening in the wall 18 of body casting 13. The cylindrical rotor member 38 includes a threaded opening or bore 49 (see Fig. 2) through which a threaded tool or one of the bolts 40 may be threaded. Opening or bore 49 is positioned so that the bolt by abutting the end of hub 33 may act as a puller to draw or pull the member 38 off of member 33.

From the foregoing description it will be obvious that a grinder rotor is provided by this invention having improved construction wherein the rotor assembly includes members having cam surfaces which cooperate to clamp the rotor assembly upon the motor shaft and to clamp the ring members of the assembly that carry the material reducing elements thereto. It will also be seen that there is provided a material reducing rotor that may be removed readily from the grinder merely by the loosening of a clamping device and that the rotor assembly when replaced upon the shaft may be locked thereto merely by the tightening of the clamping device and that when the clamping device is tightened all of the parts of the rotor assembly are tightened together.

One of the chief advantages flowing from the invention is the fact that it provides a rotor in which substantially the only wearing or expendable parts are the identical rings 42. Rings 42 are relatively easily and inexpensively manufactured, and the body member 38 of rotor assembly 21 is readily removable from the grinder to facilitate the replacement of the rings 42.

Obviously those skilled in the art may make various changes in the details and arrangement of parts without departing from the spirit and scope of the invention as defined by the claim hereto appended, and applicant therefore wishes

not to be restricted to the precise construction herein disclosed.

Having thus described and shown an embodiment of the invention, what it is desired to secure by Letters Patent of the United States is:

5 A grinder rotor assembly including ring members carrying material reducing teeth and adapted to be mounted upon a shaft, said assembly comprising a hub having an outer tapered surface split radially and axially to make the hub compressible when mounted on said shaft, the hub having a shouldered bore providing a keyway for receiving a key in said shaft, a cylindrical rotor body carried on said hub and having a tapered bore adapted to be received over the outer tapered surface of said hub, said rotor body being split radially and axially to make the rotor body expansible when mounted on the hub, said tapered surfaces of the hub and rotor body engaging to form cam surfaces which cause the hub to be compressed on said shaft and the rotor body to be expanded within said ring members when the rotor body is clamped upon the hub, means for drawing the rotor body over the hub whereby said rotor body and hub are clamped together, said ring members being carried on the outer surface of said rotor body and having said teeth equally radially spaced thereon, and said ring members having a slot to receive a key for locking the ring members to said rotor body whereby the ring members can be mounted with the teeth of alternate ring members staggered radially with respect to each other.
